UNITED STATES PATENT OFFICE.

HENRI MAROIS, OF LEWISTON, MAINE.

INSTRUMENT FOR APPLYING LIQUID FINISH TO SHOES.

1,253,408.

Specification of Letters Patent. Patented Jan. 15, 1918.

Application filed May 14, 1917. Serial No. 168,350.

To all whom it may concern:

Be it known that I, HENRI MAROIS, a citizen of the United States, residing at Lewiston, in the county of Androscoggin and 5 State of Maine, have invented certain new and useful Improvements in Instruments for Applying Liquid Finish to Shoes, of which the following is a specification.

This invention relates to improvements in 10 devices for applying liquid material, paint or blacking for instance, to the welt or edge of a shoe. Hitherto for the most part this has been done by hand with an ordinary brush, which requires great care, skill and 15 much time. The object of the present invention is to provide a device by which this work may be done with greater rapidity and uniformity.

In the drawing herewith accompanying 20 and forming a part of this application Figure 1 is an elevation partly in section of my improved device, showing it adapted to operate on the welt; Fig. 2 is a detail sectional view of a portion of the brush carrying feed pipe and its adjusting valve; Fig. 25 3 is a detail view showing the vessel closure and means for supporting the guiding mechanism; Fig. 4 is a detail view of a guide for operating on the edge of the sole, and Fig. 5 is a detail view showing means 30 for preventing the rotation of the brush carrying pipe in the closure.

The same reference characters indicate 35 like parts in the several figures.

In said drawings 1 is a container for the material being used, 2 a closure therefor and 40 3 a tank for air under pressure which has an open connection with said container. Any convenient means may be employed 45 for filling the air tank, of which I have illustrated a simple one which consists in providing the tank with an inlet pipe 4 in which is mounted a float check valve 5. The tank may be filled with air under pressure 50 by blowing into the inlet pipe 4 or by an air pump. Inserted in the container, preferably through the closure, is a pipe 6, and for convenience the outer end is curved as shown at 7. In the end of this pipe is inserted a brush 8 which has one or more openings 9 therein. At a convenient point 55 in the pipe is a stop 10 having a longitudinal opening 11 therein. Extending transversely through the pipe and stop is a reciprocating valve 12 provided with an opening 13. The valve is held by a spring 14 normally in position so that opening 13 is 60 out of register with opening 11. Any convenient spring device may be used for the purpose. I have shown a flat spring having one end attached to a bracket 15 mounted on the pipe and the other end bifurcated, as seen at 16, to loosely engage the valve stem. The spring is held in place by an adjusting nut 17. By means of nut 17 the valve can 65 be adjusted so that if desired only a predetermined portion of opening 13 can be brought to register with the opening 11. Pivottally attached to the opposite side of pipe 7 or to a bracket 15 is a lever 18, the upper end 19 of which is bifurcated and 70 slidingly engages valve 12 and the lower end of which is provided with a handle 20. Slidably mounted on pipe 6 is a sleeve 21 which may be locked thereto by means of 75 a set screw 22. The sleeve supports an arm 23 to which is secured in any convenient manner a guide carrier 24. As shown, mounted in this carrier is a guide of any suitable form and structure adapted to engage and move along the outside of a shoe and positioned relative to the brush so that the brush will engage the desired part of the shoe as the device is moved relative to the shoe. In Fig. 1, I have shown a guide 80 25 adapted to be used when applying the material to the welt. It is preferably a plate mounted on a yielding spring 26 secured to a plunger 27 yieldingly mounted in the carrier and adjustable by means of a threaded 85 nut 28. In Fig. 4 I have shown a guide 20 adapted to be used with the brush when material is being applied to the edge of the sole. This consists of a U-shaped member 29 secured to plunger 27. The brush is 90 mounted between the arms of the U-shaped member which embrace the edge of the sole and slide in engagement therewith. The space between the arms of the U-member may be adjusted to fit soles of varying thickness by means of a threaded bolt 30. The air tank may be provided with a pipe 31 95 passing through the container. The feed pipe may be held against rotation in the closure by means of a clamp 32 adapted to engage it and the pipe 31 to which the air tank is connected. The form and construction of many of the parts which go to make up this device may be varied and still be within the scope and spirit of my invention.

I claim:

1. In a device of the character described,

a liquid container, means for maintaining the liquid in the container under pressure, a feed pipe entering the container, a brush in said pipe, a valve in said pipe, means for 5 opening said valve and a guide located adjacent said brush and adapted to be moved manually in contact with some part of the work.

2. In a device of the character described, 10 a liquid container, means for maintaining the liquid in the container under pressure, a feed pipe inserted in the container, a brush in said pipe, a valve in said pipe, means for opening said valve, means for varying the 15 opening in said valve and a guide located adjacent said brush and adapted to be moved manually in contact with some part of the work.

3. In a device of the character described, 20 a liquid container, means for maintaining the liquid in the container under pressure, a feed pipe entering the container, a brush in said pipe, a valve in said pipe, means for opening said valve and a guide yieldingly 25 mounted adjacent said brush and adapted to be moved manually in contact with some part of the work.

4. In a device of the character described, 30 a liquid container, means for maintaining the liquid in the container under pressure, a feed pipe entering said container, a brush in said pipe, a valve in said pipe, means for opening said valve, a guide located adjacent said brush and adapted to be moved manually 35 in contact with some part of the work and means for adjusting said guide relative to said brush.

5. In a device of the character described, a liquid container, means for maintaining

the liquid in the container under pressure, 40 a feed pipe entering the container, a brush in said pipe, a valve in said pipe, means for holding said valve yieldingly closed, means for opening said valve comprising a hand lever loosely engaging the stem thereof and 45 a guide located adjacent said brush and adapted to be moved manually in contact with some part of the work.

6. In a device of the character described, 50 a liquid container, means for maintaining the liquid in the container under pressure, a feed pipe inserted in the container, a brush in said pipe, a valve in said pipe, means for opening said valve and a U-shaped guide located adjacent said brush and adapted to 55 inclose said brush and the work and be moved manually in contact with the work.

7. In a device of the character described, 60 a liquid container, means for maintaining the liquid in the container under pressure, a feed pipe entering the container, a brush in said pipe, a valve in said pipe, means for opening said valve, means for preventing 65 said pipe from rotating relative to the container and a guide located adjacent said brush and adapted to be moved manually in contact with some part of the work.

8. In a device of the character described, 70 a liquid container, means for maintaining the liquid in the container under pressure, a feed pipe inserted in the container, a brush in said pipe, a valve in said pipe, means for manually opening said valve and a guide located adjacent said brush and adapted to be moved manually 75 in contact with some part of the work.

HENRI MAROIS.
